UNITED STATES PATENT OFFICE.

HENRY CARL BARTH, OF HELENA, MONTANA.

MAIL BOX.

Application filed April 10, 1925. Serial No. 22,174.

To all whom it may concern:

Be it known that I, HENRY C. BARTH, a citizen of the United States, and a resident of Helena, in the county of Lewis and Clark 5 and State of Montana, have invented certain new and useful Improvements in Mail Boxes, of which the following is a specification.

My invention relates to improvements in 10 boxes of the type having a plurality of separate compartments for the reception of mail or other small articles, and it consists in the combinations, constructions and arrangements herein described and claimed.

An object of the invention is to provide 15 a box of the character described which affords facilities for preventing unauthorized removal of articles from the individual compartments of the box, and which at the same time, permits an authorized person to have access to all compartments at the same time.

A further object of the invention is the provision of a box of the character described having a main door for closing a 20 plurality of compartments provided in the box simultaneously, the main door carrying doors for the individual compartments.

A further object of the invention is the provision of a box of the character described which is inexpensive to manufacture, is strong and durable, reliable in use, and thoroughly practical commercially.

Other objects and advantages of the invention will be apparent from the following 25 description considered in conjunction with the accompanying drawings, in which:

Figure 1 is a perspective view of a box embodying the invention supported in an opening in a wall,

Figure 2 is a relatively enlarged section 30 substantially along the line 2-2 of Figure 1,

Figure 3 is a front view of the box with the door thereof partly raised, portions of the box being broken away to show elements that would otherwise be hidden, and

Figure 4 is a fragmentary horizontal sectional view of the box.

The improved box has a body made of 35 sheet metal or other suitable material and comprises a bottom 1, a back 2, side walls 3,

and a top 4. The space within the body of the box is divided by intersecting vertical and horizontal partitions 5 and 6 into a plurality of compartments 7, each of which is open at the front as best seen in Figure 3. The body of the box has a rim portion thereof mounted in a frame which comprises a bottom member 8, a pair of side members 9, and a top member 10. This frame may 40 be mounted in an opening 11 in a wall 12 or may be supported in any other suitable known manner. The top member 10 of the frame is formed to provide a longitudinal slot 13 and vertical side grooves or guide-ways 14 are provided at the inner sides of the side members 9 of the frame for the reception of the side edge portions 15 of a door 16 which is slideable vertically from position to close all the compartments 7 45 through the slot 13 to position to uncover the front ends of all the compartments 7. A groove or channel 17 is provided in the upper face of the lower or bottom member 8 of the frame in which the lower edge portion 18 of the door 16 seats when the door is closed. The bottom member 8 may have a key hole opening 19 leading to a suitable lock, not shown, which is carried by the bottom member 8 in position to engage with 50 a keeper 20 on the lower edge portion of the door when the door has been moved downward to closed position as shown in Figure 1. Stops 21 on the lower edge portion of the door engage with the bottom member 8 of the frame when the door is in 55 fully closed position and relieve the lock of undue strain.

The door 16 has openings 22 corresponding in number and relative arrangement 60 with the compartments 7, each opening 22 being directly in front of and adjacent to the corresponding compartment 7 when the door 16 is in closed position. A door 23 is provided for each opening 22 and is attached by means of a hinge 24 to the main door 16. It therefore will be manifest that each door 23 serves not only as a door or closure for its particular opening 22, but also as a means for preventing access to a 65 particular compartment 7 when that door 23 and the main door 16 are closed. Each door

23 may be kept closed by any suitable lock, none being shown, so that opening of the door 23 by an unauthorized person will be practically prevented.

5 In order that the main door 16 shall be capable of easy movement in the guideways 14 from closed to open position, I may make use of weights as shown at 25 in Figure 3, each weight 25 being suspended in 10 a vertical passageway 26 in one of the side members 9 of the box body supporting frame, by a cable 27, the cable being passed over a guide sheave 28 at the upper end of the side member 9 and being extended downwardly in the adjacent guideway 14 and attached at its lower end to the door 16 adjacent to the lower edge of the latter, as by means of the bracket 29. The weight 25 may be effective to raise the door as soon as 20 the keeper 20 has been released from the bottom member 8 of the frame, although preferably some slight manual action will be required in addition to the action of the weight 25 to raise the door to open position. The stops 21 will contact with the 25 upper frame member 10 and will prevent the door from moving entirely through the slot 13.

From the foregoing description of the 30 various parts of the device, the operation thereof may be readily understood. Each compartment 7 may have a plate 30 in the front part thereof for carrying the name of the user of the compartment in position 35 to be visible from the space at the front of the box, the name being produced on a strip secured to the plate 30 or marked on the latter in any suitable known manner. If desired, each door 23 may have a glass 40 panel to permit a view of the name on the plate 30 in the compartment 7 with which that door 23 is associated.

When the box is used for the reception 45 of mail, the postman who delivers the mail will of course have a key for the lock of the main door and on releasing the main door and raising it to open position, he will have access to all the compartments 7. However, when the main door is closed and 50 locked, access to the compartments 7 can be had only through the openings 22 for which the doors 23 are provided. It is intended that each door 23 shall have a lock so that the user of each compartment 55 will have exclusive use thereof and the contents of each compartment 7 will be protected against theft and cannot be inspected by unauthorized persons.

Obviously the improved box may be used 60 to good advantage for the reception of articles other than mail.

Obviously the invention is susceptible of embodiment in forms other than that which is illustrated in the accompanying drawings, 65 and I therefore consider as my own all such

modifications and adaptations thereof as fairly fall within the scope of the appended claims.

I claim:

1. A box of the character described comprising a hollow body open at the front, a frame supporting the rim of said hollow body, said frame having a slot in the upper member thereof and having guideways in the inner faces of the side members thereof, partitions within said body dividing the space within the latter into a plurality of compartments, each open at the front of the body, a door extending slidably through said slot in the upper part of the frame and in sliding engagement at its side edges with said guideways and the side members of the frame, said door being movable to and from position to cover the fronts of all of said compartments, said door having an opening for each of said compartments, each opening of the door being at the front of the corresponding compartment when the door is closed, and a door for each of the openings in said first named door. 70 75 80 85 90 95

2. A box of the character described comprising a hollow body open at the front, a frame supporting the rim of said hollow body, said frame having a slot in the upper member thereof and having guideways in the inner faces of the side members thereof, partitions within said body dividing the space within the latter into a plurality of compartments, each open at the front of the body, a door extending slidably through said slot in the upper part of the frame and in sliding engagement at its side edges with said guideways and the side members of the frame, said door being movable to and from position to cover the fronts of all of said compartments, said door having an opening for each of said compartments, each opening of the door being at the front of the corresponding compartment when the door is closed, a door for each of the openings in said first named door, a stop on the lower edge portion of said door for engaging with the frame to limit the vertical movement of the door. 100 105 110 115 120

3. A box of the character described, comprising a hollow body open at the front, a frame supporting the rim of said hollow body, said frame having a slot in the upper member thereof and having guideways in the inner faces of the side members thereof, partitions within said body dividing the space within the latter into a plurality of compartments, each open at the front of the body, a door extending slidably through said slot in the upper part of the frame and in sliding engagement at its side edges with said guideways and the side members of the frame, said door being movable to and from position to cover the fronts of all of said compartments, each opening of 125 130

the door being at the front of the corresponding compartment when the door is closed, and a door for each of the openings in said first named door, one of the side members of the frame having a vertical passage therein at the outer side of the vertical guideway in said side member, said vertical passage being in open communication at its upper end with said guide-

way, a guide sheave in the upper end of 10 said vertical passage, a cable attached at its lower end to the lower edge portion of said door and extending upwardly in the adjacent guideway across said sheave and downwardly in said vertical passage, and 15 a weight suspended by said cable for movement vertically in said passage.

HENRY CARL BARTH.
